DESIGN FOR A JEWELRY FINDING FOR PINS OR OTHER SIMILAR ARTICLES OF JEW- ELRY

Sidney N. Stone, Cedarhurst, N. Y.

Application March 29, 1941, Serial No. 99,991

Term of patent 3½ years

To all whom it may concern:

Be it known that I, Sidney N. Stone, a citizen of the United States, residing in Cedarhurst, in the county of Nassau and State of New York, have invented a new, original, and ornamental Design for a Jewelry Finding for Pins or Other Similar Articles of Jewelry, of which the following is a specification, reference being had to the accompanying drawing, forming part thereof, in which—

Figure 1 is a plan view of a jewelry finding for pins or other similar articles of jewelry showing my new design;

I claim:

The ornamental design for a jewelry finding for pins or other similar articles of jewelry, as shown.

SIDNEY N. STONE.
